Joseph J. Stoetzel INVENTOR.

BY
W. P. Biddle ATTORNEY.

UNITED STATES PATENT OFFICE.

JOSEPH J. STOETZEL, OF BELLAIRE, NEW YORK, ASSIGNOR TO G. & G. ATLAS SYSTEMS, INC., A CORPORATION OF NEW YORK.

PNEUMATIC-CARRIER CHECK.

Application filed May 23, 1924, Serial No. 715,301. Renewed January 16, 1926.

It often happens, in the construction of a pneumatic despatch tube system, that it is desirable to provide for a sheer drop, or nearly vertical slide, at some place in the system of tubing. It is well known that in large systems, the transit tubes assume many angles of travel, upward, downward, as well as level. And it is also well known that the atmospheric pressure behind the carrier remains substantially the same while the exhauster is creating the maximum, or carrier driving, flow. When, therefore, a carrier takes a sudden drop or plunge downward the accrued momentum of the carrier is added to the speed derived from the driving atmosphere, and converted into increased flight by reason of gravity of the carrier. At such times it becomes desirable to check the speed of the falling carrier for obvious reasons.

The object of my invention is to provide a simple and effective checking device, operated pneumatically by the increased air-pressure itself, to counteract the tendency of the carrier to acquire a dangerously increased speed. And to make this checking device such that it is always ready to act upon the emergency call, although normally idle.

To this end my invention consists, broadly, in a pneumatic carrier check, located in, or communicating with, a transit tube of a pneumatic despatch tube system, especially where a sharp drop or steep declivity exists, and comprising a movable plate blade, or other partly-damming device, adapted to choke to a desired extent the passage of air preceding a carrier, when tending to move too rapidly,—and a diaphragm-valve, or equivalent device, adapted to be operated by the increased pressure incident to the too rapid movement of the carrier, and thus bring said choking device into action.

As a preferred form of my improved checking device I have shown, in the accompanying drawing, a pneumatic carrier check involving my invention,—the damming device being shown as a thin plate hanging inside a transit tube of a pneumatic despatch tube apparatus,—a casing secured to the outside of said tube and communicating with the interior of said tube

by suitable ports,—and a diaphragm valve for operating said damming device,—the diaphragm chamber being a part of said casing but with one side of the diaphragm always open to the atmosphere.

In this drawing:—

Fig. 1 is a diagrammatic sketch of a portion of a pneumatic despatch tube system of the open current type, without any attempt to show proportions or any details except to illustrate the fact that my improved carrier check is to be interposed in such a system near the heel of a drop, and between the open bell-mouth (not shown) and the discharge-outlet,—which discharge-outlet is, naturally above the control-valve, and the exhauster.

Fig. 2 is a vertical section on a larger scale of my improved pneumatic carrier check.

Fig. 3 is a horizontal section on line 3—3 of Figure 2.

Same letters indicate similar parts in the different figures.

A, represents a carrier as descending in a transit tube of a pneumatic despatch tube system not shown above the break. B, is the transit tube which continues to the discharge outlet C, after which it becomes the exhaust tube D. E is a valve-casing enclosing any suitable air-control-valve, and F, is the exhaust drum which here stands for the usual exhauster, including motor and governor.

All these details are of usual and suitable construction and should, therefore, be readily understood without further explanation.

G, in Figure 1, stands generally for my improved carrier check, which, however, is there shown only diagrammatically. The detailed construction is shown in Figures 2 and 3.

H, is a casing of suitable form to secure an air-tight communication between the interior of the transit tube B, and the diaphragm valve I, upon the action of which depends the movement of the plate K. L, is a flexible diaphragm which, though shown in Figure 2 as extended, is normally collapsed into the casing H, by reason of the fact that the outer side of the diaphragm is always exposed to the atmospheric pressure

and it is only when the air-pressure inside the casing (and the transit tube ahead of the carrier) exceeds atmospheric pressure that the diaphragm bulges outwardly as shown.

At the centre of this diaphragm is a plate or disc M, to which is fastened a link N, the other end of which is pivoted in a yoke O. This yoke is mounted on the outer end 10 of the choking device K, which swings on the hinge P, in the port Q through which air-communication is had between the casing H, and the inside of the tube B, by the small holes R, R.

15 The operation of my improved carrier check is as follows:—

Before a carrier in transit reaches the portion 20 of the transit tube in which occurs the drop or descent wherein the carrier check is located, said check, so far as the plate or damming device is concerned, is idle, the plate hanging in a downward direction as shown in dotted lines close to the inner wall 25 of the transit tube, and the diaphragm collapsed. As soon as a carrier drops or descends too rapidly for safety or for desired 30 operation of the system, the air ahead of the carrier banks up, creating a temporary pressure greater than atmospheric. Some of this 35 over-pressure air passes through the holes R, R, into the casing H, back of the collapsed diaphragm L, and forces the diaphragm outwardly into the extended position shown in Figure 2. This action mechanically pulls 40 the yoke O, and with it the plate K, from the position shown in dotted lines into that shown in full lines, with the result that the lower portion of said plate swings upwardly inside the transit tube and partly cuts off the flow of air. The air thus held back by 45 the partial closing of the plate K, increases the density of the air between said plate and the approaching carrier and acts as a

cushion to stay the movement of said carrier.

The duration of this cushioning effect, of course, depends upon the degree of density created by the fall of the carrier to that point and the time which it may take for this denser air to creep by the free end of the plate K, after the fall or downward motion of the carrier has been checked. When the air has thus become equalized by the disappearance of the cushion, the plate K again falls to its normal hanging position and the carrier is free to move quietly to the discharge outlet C.

The uses and advantages of my invention will, I think, be readily understood without further explanation.

I claim:—

1. A pneumatic carrier check which comprises a current-choking device, adapted to interpose itself in the path of an approaching carrier and thereby form a retarding cushion of air between said carrier and said device to diminish the speed of said carrier, and pneumatic means set in action by the increasing density of the air ahead of said carrier to cause said choking device so to 70 interpose.

2. In a pneumatic tube system, a device for checking excessive speed of carriers and means responsive to the increase in pressure within the system produced by the excessive 75 speed of a carrier, for rendering said checking device effective.

3. In a pneumatic tube system, a device adapted, when rendered effective, to cause 80 the formation of a retarding cushion of air in advance of a carrier passing through the system, and pneumatic means responsive to a change of pressure conditions within the system resulting from the excessive speed of a carrier, for rendering said device effective.

JOSEPH J. STOETZEL
